UNITED STATES PATENT OFFICE.

REINHOLD SCHOELL, OF STAMFORD, CONNECTICUT, ASSIGNOR TO THE YALE & TOWNE MANUFACTURING COMPANY, OF STAMFORD, CONNECTICUT, A CORPORATION OF CONNECTICUT.

LOCK.

943,471.

Specification of Letters Patent. Patented Dec. 14, 1909.

Application filed August 19, 1908. Serial No. 449,317.

To all whom it may concern:

Be it known that I, REINHOLD SCHOELL, of Stamford, in the county of Fairfield and State of Connecticut, have invented certain new and useful Improvements in Locks, and do hereby declare the following to be a full, clear, and exact description of the invention, such as will enable others skilled in the art to which it appertains to make and use the same.

My invention relates to an improvement in locks adapted more particularly for use in hotels, the object being to provide a lock the bolt of which may be actuated under certain conditions by the knobs, and under other conditions by one or two cylinder lock mechanisms operable through the front of the door.

A further object is to provide a lock, the bolt of which may be dead-locked by means actuated from the inside, combined with key mechanism operable through the front of the door, for disengaging said dead locking means and for retracting the bolt.

A further object is to provide a lock with bolt mechanism, and with two key cylinders, one of which is operable to release and retract the bolt when the latter has been deadlocked either from the inside or the outside, and the other only operable to release and retract the bolt when the latter has been deadlocked from the outside by either of the keys.

A further object is to provide improved means for indication both on the inside and outside, the condition of the lock.

With these and other objects in view my invention consists in the parts and combinations of parts as will be more fully described and pointed out in the claims.

In the accompanying drawings, Figure 1 is a view of the lock from the outer side showing the two key cylinders and indicator. Fig. 2 is a similar view from the inner side showing the thumb piece by which the latch bolt is locked from the inside. Fig. 3 is a view of the lock with the cover plate removed showing the auxiliary bolt retracted and the latch bolt unlocked and free to be retracted by the knob or by either the upper or lower cylinder lock. Fig. 4 is a similar view showing the parts in their position when locked from the inside by the thumb piece, in which position the bolt is deadlocked against the knobs and lower cylin-

der. Fig. 5 is a view showing the slide 45 in its intermediate position, which represents the parts when the bolt is deadlocked by a key from the outside. Fig. 6 is a view of the cam lever, the auxiliary deadlocking lever, the main deadlocking lever and the deadlocking slide, in their assembled positions. Fig. 7 are views in plan and also edge elevation of the deadlocking lever. Fig. 8 are similar views of the auxiliary 65 deadlocking lever, Fig. 9 are similar views of the cam lever and Fig. 10 is a view in section of the outside indicator.

1 represents a lock case, 2 the latch bolt and 3 the auxiliary bolt, the latch bolt and 70 the auxiliary bolts being forced outwardly by springs in the ordinary manner.

4 is a lever actuated by the hub or roll back 5, through which the spindle 6 of the knob 7 passes, the free end of lever 4 engaging cross head 8 on the inner end of the stem 9 of the latch bolt.

10 is a deadlocking lever mounted on the pin 11 secured to the case 1. This lever is provided with four arms or members 12, 13, 80 14 and 15, the former of which lies in the path of cross head 16 on the stem 17 of the auxiliary bolt 3, and when the auxiliary bolt is projected, is engaged by said cross head and holds deadlocking member 13 of lever 85 10 out of the path of bolt 2, thus leaving the latter free to be forced inwardly as the door is closed.

In the operation of the lock, the auxiliary bolt 3, is adapted to engage the strike plate 90 and be held retracted when the door is closed, and when in such retracted position, it releases the deadlocking lever 10, thus permitting the spring 18 to turn the latter in a direction to bring the end of arm 13 in rear 95 of the bolt 2, (which when the door is closed, has entered its seat in the strike plate) thus deadlocking the bolt against retraction, by a thin instrument inserted against the bevel face of the bolt intermediate the face and 100 strike plates of the lock.

19 is the actuating lever of the upper cylinder lock. This lever is pivotally mounted on the pin 20, and is provided with a spring 21 which tends to hold shoulder 22 of the 105 lever 19 away from the cross head 8 of bolt 2, its movement away from said cross head, being limited by the fixed stop 23.

Mounted on pin 11, and resting in front of and against the deadlocking lever 10, is the 110

cam lever 24, provided at its free end, on its inner side, with a lug 25 resting in contact with the inclined face 26 at the free end of bolt actuating lever 19, and at its free end, 5 on its outer side, with an integral lug 24^a, adapted to be engaged by the cam 27 on the inner end of the revolving plug 28 of the upper cylinder lock 29, hence when the plug 28 is turned by its proper key, its cam 27 10 engages lug 24^a and turns cam lever 24, thus moving its lug 25 in contact with the inclined face 26 of lever 19. This engagement of the lever 24 with lever 19, turns the latter on its pivot 20 in a direction to cause its 15 shoulder 22 to engage and move the cross head 8 rearwardly in a direction to retract bolt 2.

Mounted on pin 11, in contact with and in front of cam lever 24, is the auxiliary deadlocking lever 29. This lever 29 is provided with three arms or members, the arm 30 of which is provided with a pintle 31 carrying one end of the connecting bar 32, the opposite end of said bar being pivotally connected to pintle 33 on cam lever 34, pivoted near the lower end of the lock case 1, and in a position where its free end 35 may be engaged, and the lever moved, by the cam 36 carried by the plug 37 of the lower cylinder lock 38. Lever 29 is also provided with a lug 40, which rests above and in contact with the upper edge of cam lever 24.

The upper cylinder lock 29^a together with the lower cylinder lock 38, are accessible only 35 from the outside of the door, the upper lock being operable by one or a plurality of keys, such as guest's or change key and an emergency key, and the lower lock being operable by one or a plurality of keys, such as maids' 40 and master keys.

From the foregoing it will be seen that the bolt 2 may be retracted by the lower lock 38 through lever 34, bar 32, auxiliary deadlocking lever 29, lug 40, cam lever 24 and 45 bolt actuating lever 19, while the bolt 2 may be retracted by the upper lock through cam lever 24 and bolt actuating lever 19. When the bolt 2 is not deadlocked, it may also be retracted by the knobs from either side of 50 the door.

When the door is closed, and the bolt deadlocked by the lever 10, the latter must, in order to release the bolt, be moved out of the path of the latter by mechanism actuated by 55 the thumb piece from the inside, or by the keys of the cylinder locks 29^a or 38, from the outside. This is accomplished by the key locks from the outside through the arm 15, on lever 10, normally resting in the path of 60 the free end of the bolt actuating lever 19. This lever 19 as previously explained, is actuated by both locks, and as it is turned its free end engaging shoulder 41 on arm 15 of lever 10, turns the latter in a direction 65 to elevate the deadlocking arm 13, and holds

it in such position until the lever 19 has been released.

The bolt is actuated from the inside by the knob, and is locked from the inside by the thumb piece 42. This thumb piece is connected to the hub 43, to which is pivotally connected one end of the link 44, the opposite end of said link being connected to the slide 45. This slide 45 is mounted in the lock case above the bolt 2 and is adapted to 75 be moved toward and away from the face plate 46 of the lock, by the thumb piece 42, and is yieldingly held in its several positions by the spring catch 47 engaging the notches 48 formed in the lock case near the top 80 thereof. There are three notches 48 in the lock case, and when the toothed end of the spring 47 is in the notch farthest removed from the face plate 46, the arm 13 of deadlocking lever 10, will be held out of the path 85 of the bolt by the engagement of the slide 45 with the arm 14 of the deadlocking lever 10 thus holding arm 13 of the latter out of the path of bolt 2 and permitting the latter to be freely actuated by the knob from either 90 side of the door; when the toothed end of the spring is in the second notch, which is the position into which the parts are moved from the innermost position of the spring catch 47 when the bolt is locked by a key 95 from the outside, the deadlocking lever 10 rests in its deadlocking position, but may be actuated as above explained, by either the upper or lower cylinder locks, and when the toothed end of the spring is in the notch 100 nearest the face plate of the lock, which is the position into which the parts are moved by the thumb piece when locking the door from the inside, the shoulder 50, to be hereinafter referred to, on the slide 45 rests in 105 the path of arm 51 on lever 29 thus deadlocking the latter and preventing the bolt from being actuated by the lower cylinder lock, which as previously explained, is adapted to be actuated by the maid's key and by a master key. This last position described, represents the position of the parts when the guest is in his room and the door locked. When the slide is in its position farthest removed from the face plate 46, it engages arm 14 of 110 deadlocking lever 10 as previously stated and holds arm 13 up and out of the path of the bolt, thus leaving the latter in its unlocked position and free to be retracted by either 115 knob.

When the door is closed and the slide 45 in its position against the face plate 46 of the lock, the bolt will be deadlocked against the knobs and also against the lower lock 38, but may be opened by the guest's key or emergency key in the upper lock. When the door is open, the auxiliary bolt, as before explained, holds the deadlocking arm 13 of lever 10, out of the path of the bolt 2. If, when the door is open, the slide 45 be moved 120

5 by thumb piece 42, either through accident or design, into its position adjacent the face plate 46, and the door be then closed, the direct pressure of the head of the bolt against the slide, will overcome the friction of the 10 spring 47 and forcibly push the slide rearwardly to its innermost position. The slide in its inward movement, makes contact with the short arm 14 of deadlocking lever 10, thus turning the latter in a direction to carry its arm 13 out of the path of the bolt 2 so that when the door reaches its closed position, the bolt will be unlocked or free to be retracted by the knob.

15 The bolt is locked from the inside solely by the thumb piece and is locked from the outside by turning the plug of either cylinder lock in one direction, and is unlocked from the outside by turning the plug of the lock in 20 the opposite direction.

25 It will be seen that when the door is closed and the slide 45 is in its position farthest removed from the face plate 46, the deadlocking arm 13 of the deadlocking lever 10 will be held out of the path of the bolt 2, by the engagement of the slide 45 with the arm 14 of the deadlocking lever 10, thus leaving the bolt 2 free to be actuated by the knobs. If the door be closed with the parts in the 30 position last described, and the guest's, maid's or other key be inserted and turned to the left, a whole revolution, or in the direction opposite to that which it is turned to unlock the lock, the arm 29^b of the auxiliary deadlocking lever 29, shifts the slide 45 toward face plate 46 in center notch, a distance sufficient to release the arm 14 and thus permit the deadlocking lever to turn until its arm 13 is in a position to deadlock the bolt.

35 40 When the door is locked from the inside by the thumb piece 42, the shoulder 50 on the slide forms an abutment for the arm 51 on the auxiliary deadlocking lever 29, and as the lower lock 38 transmits motion to the 45 bolt actuating lever through lever 34, bar 32, auxiliary deadlocking lever 29, and cam lever 24 in the order named, it follows that if the auxiliary deadlocking lever be dogged by the slide plate, the bolt cannot be retracted by the lower lock, but is free to be retracted by an emergency key or the guest's key introduced in the upper lock, which operates directly through cam lever 24 and bolt retracting lever 19.

45 50 55 For the purpose of indicating on the inside and also on the outside, the condition of the lock, I have provided two indicators, one of which is a plate 52 attached directly to the spindle of the thumb piece, and showing 60 through a slot 53 in the escutcheon plate 54 of the lock, and having thereon the words "Locked" and "Open", the words being so located as to show through the slot 53 and correctly indicate the condition of the lock 65 to the guest or person within the room, and

the other indicator is a plug 55 mounted in the outer escutcheon plate 56 above the upper lock 29. This plug has an angular outer end which rests in a correspondingly shaped opening in escutcheon plate 56, the shape 70 of the plug and the opening in the escutcheon plate, preventing the plug from rotating after the parts have been assembled. The plug passes through the door in rear of the escutcheon plate 56, and its inner screw 75 threaded end is screwed into the plunger 61 mounted in the sleeve 56^a carried by and projecting inwardly from the lock case. This plunger 61 is provided at its inner end with a head 57 against which one end of the 80 spring 58 bears, the spring tending to normally hold the plug 55 retracted with its outer end approximately flush with the outer face of the escutcheon plate 56 which is its normal position when the door is not locked. 85 The slide 45 is provided with a tail piece 59 provided at its rear end with a cam 60 adapted when the slide 45 is moved to its position adjacent to the face plate 46 of the lock to engage the plunger 61 and move the 90 latter outwardly causing the outer end of plug 55 to project beyond the escutcheon plate, and indicate by its position, which can be seen by the chambermaid or other person on the outside, that the room is 95 locked from the inside.

95 By making the indicator of two parts extensible by reason of their threaded connection, the indicator may be adjusted as to length so as to be accurately fitted to doors 100 of different thicknesses.

100 When the door is locked from the outside by a key, the slide 45 is only pushed one tooth, which is not sufficient to cause the cam to engage the plunger, consequently 105 when the indicating plug is in, and the door locked, it indicates at once to the maid that the room is empty.

110 With my improved lock, after the latch bolt has been deadlocked from the outside by a key, the latter may be turned all the way around without making contact with any fixed or immovable part, hence the insertion and turning of the key in the usual manner will lock the bolt if the latter be 115 unlocked, or if it be locked, the key will turn without meeting any fixed obstruction thus avoiding the liability of breaking the key by forcing it against a fixed stop.

120 It is evident that changes in the construction and relative arrangement of the several parts might be made without avoiding my invention and hence I would have it understood that I do not restrict myself to the particular construction and arrangement of 125 parts shown and described, but—

Having fully described my invention what I claim as new and desire to secure by Letters-Patent, is,—

1. The combination with a lock casing, 130

bolt and deadlocking means for the bolt, of devices operable from the inner side of the door for shifting the deadlocking means, and two cylinder locks operated by keys from the outer side of the lock for operating the deadlocking means and also for retracting the bolt.

2. The combination with a lock casing, bolt and deadlocking means for the latter, of means operable through the inner side of the lock for actuating the deadlocking means, to lock and release the bolt, means operable through the outer side of the lock for actuating the deadlocking means and two cylinder locks actuated by keys through the outer side of the lock, one of said cylinder locks adapted to move the deadlocking means to release the bolt when the latter has been locked either from the outside or the inside, and the other adapted to operate the deadlocking means only when the latter has been set by a key from the outside.

3. The combination with a lock casing, a bolt and means for deadlocking the bolt, of knob and key mechanism operable from the outer side of the lock, means operable from the inner side of the lock for deadlocking the bolt against said knob and key mechanism, and a second key mechanism adapted by a single partial rotation to release the deadlocking mechanism and retract the bolt.

4. The combination with a lock casing, a bolt and means for deadlocking the latter, of a knob and a key mechanism operable from the outer side of the lock, and means operable from the inner side of the lock for deadlocking said bolt against the knob and key mechanism, and a second key mechanism and connections for releasing the bolt when the latter has been deadlocked from the inner side.

5. The combination with a lock casing, a bolt and means for deadlocking the latter, of two independent key mechanisms operable through the outside side of the lock casing, means directly actuated by one of said key mechanisms for retracting the bolt, the other key mechanism being connected to and operating to retract the bolt through the means actuated directly by the first mentioned key mechanism.

6. The combination with a lock casing and a bolt, of two separated key mechanisms operable through the outer side of the lock, means actuated by each of said key mechanisms for retracting the bolt, deadlocking means for said bolt operable from the inner side of the door, and means connecting one of said key mechanisms and the deadlocking means, whereby when the latter is deadlocking the bolt it can be released by said key mechanism.

7. The combination with a lock casing, a bolt and a knob mechanism, of deadlocking means for the bolt, mechanism operable

from the inside of the lock for setting and releasing said deadlocking mechanism, and two lock mechanisms operable from the outer side of the lock for setting and releasing said deadlocking mechanism.

70

8. The combination with a lock casing, a bolt and knob mechanism for retracting the bolt, of deadlocking means for the bolt, means on the inner side of the lock for operating said deadlocking means, two key locks operable from the outer side of the lock for setting and releasing said deadlocking means, one of said key locks being connected to the means operated from the inner side of the lock, whereby the deadlocking means, when set from the inner side, may be released through said key lock from the outside.

75

9. The combination with a lock casing, a bolt and knob mechanism, of means operable from the inner side of the lock for deadlocking the bolt against the action of the knob, and two key locks operated from the outside, and each adapted also to deadlock the bolt against the action of the knob.

80

10. The combination with a casing, a bolt and knob mechanism, of means operable from the inside of the lock, and two key locks operable from the outside for locking the bolt against the action of the knobs, the locking operating means at the inner side of the lock also deadlocking the bolt against one of said key locks.

90

11. The combination with a bolt, knob mechanism and a deadlocking lever for the bolt, of a slide operable from the inner side of the lock and adapted to lock and release the deadlocking lever, a key lock operable from the outer side of the lock and means whereby when said key lock is actuated the slide will be moved to release the dead-locking lever.

100

12. The combination with a bolt, a deadlocking lever and knobs, of an auxiliary bolt for holding the deadlocking lever out of the path of the bolt when the door is open, shiftable means for holding said lever out of the path of the bolt when the door is closed, means operable from the inner side of the lock for moving said shiftable means whereby the bolt may be deadlocked when the door is closed, and a key lock operable from the outer side of the door, for actuating said shiftable means and for retracting the bolt.

110

13. The combination with a casing and a bolt, of a spring actuated deadlocking lever, a slide engaging the latter and adapted to move it against the action of the spring and out of the path of the bolt, a cylinder lock operable through the outer face of the lock, and means operated by said cylinder lock for shifting the slide in a direction to release the deadlocking lever.

115

14. The combination with a casing and a

120

125

130

bolt, of a spring actuated deadlocking lever, a slide engaging the latter and adapted to move it against the action of the spring and out of the path of the bolt, means operable from the inner side of the lock for shifting the slide in both directions, and a cylinder lock operable from the outside of the door and operating through connections, when the door is locked from the inside, to first shift the deadlocking lever out of the path of the bolt, and then move the bolt and slide rearwardly.

15. The combination with a bolt and deadlocking lever, of two cylinder locks, a cam-lever actuated by each, a bolt retracting lever engaging the bolt and engaged by one cam lever, and a bar and devices connecting the two cam levers, whereby the bolt may be unlocked and retracted by either 20 cylinder lock.

16. The combination with a bolt and a spring actuated deadlocking lever, of a slide engaging said deadlocking lever, a bolt actuating lever also engaging said deadlocking 25 lever, a cam lever adapted when moved in one direction to engage and move the bolt actuating lever, an auxiliary deadlocking lever engaging both the cam lever and slide, the main and auxiliary deadlocking levers 30 and cam lever having a common axis, and a

cylinder lock, the cam of which engages and actuates the cam lever.

17. The combination with a bolt, deadlocking lever and bolt actuating lever, the latter adapted to shift the deadlocking lever and retract the bolt, of a slide operable from the inside of the lock and adapted to shift the deadlocking lever, a cam lever engaging the bolt actuating lever, an auxiliary deadlocking lever engaging the cam lever and slide, a second cam lever, a bar connecting said second cam lever with the auxiliary deadlocking lever, and two cylinder locks the cams of which engage and move their respective cam levers.

18. The combination with a bolt, of a key lock, and mechanism intermediate the key lock and bolt for retracting the latter, the said mechanism adapted to give or yield under pressure of the key and permit the latter to make a complete revolution in a direction to lock the bolt, when the latter is locked.

In testimony whereof, I have signed this specification in the presence of two sub- 55 scribing witnesses.

REINHOLD SCHOELL.
